N. O. LYNN

DENTAL CASTING FLASK

Filed Nov. 19, 1921

N. O. Lynn, Inventor

By *Geo. P. Kimmel*, Attorney

UNITED STATES PATENT OFFICE.

NATHAN O. LYNN, OF TUCSON, ARIZONA.

DENTAL CASTING FLASK.

Application filed November 19, 1921. Serial No. 516,448.

To all whom it may concern:

Be it known that I, NATHAN O. LYNN, a citizen of the United States, residing at Tucson, in the county of Pima and State 5 of Arizona, have invented certain new and useful Improvements in Dental Casting Flasks, of which the following is a specification.

This invention appertains to improvements in casting flasks generally, and more particularly to a type of the same adapted to use in dental laboratory work for the casting of bridges, crowns, fillings, inlays, plates and other forms of dental restorations.

In the practice of dentistry, the casting of gold, aluminum, and other metallic alloys is accomplished by the preparing of molds for each individual case, wherein an investment, such as a body of mold forming material, is placed in the flask in plastic state, and a pattern having the form of the article to be produced is embedded within the same, the pattern being made of a volatile 25 substance, such as wax or the like, which will be destroyed by the action of heat applied to the flask for the purpose and for the driving from the investment of all of its moisture content. When properly heated, the investment will harden, and the wax pattern be destroyed, whereby a mold space or cavity will be provided for the reception 30 therein of the desired molten metal from which the article is to be produced, and this

molten metal has to be forced into the mold space or cavity, and is accomplished either by the use of a pressure or vacuum machine. When hardened, the investment is of a relatively great porosity, and, in the use of a 35 pressure machine, the molten metal is forced downwardly of the sprue hole leading into the mold space or cavity, under the action of the pressure of such machine, while in the use of the vacuum machine, the action of the same draws out all of the air from the pores 40 of the investment with the result that the molten metal is forced into the mold space or cavity under atmospheric pressure. Heretofore, in the practice and in the use of known types of dental flasks or molds, it 45 very often occurs that, by reason of inac-

curacies in the positioning of the wax pattern within the investment, the mold space or cavity is formed too near the end on the latter, so that the outer wall thereof is too 55 weak to withstand the pressure or vacuum methods of introducing the molten metal to the mold space or cavity, and is broken down, whereby the entire operation is a failure, with a consequent serious loss in 60 time, labor, and material in such operation, as well as in the preparation of a new mold and the carrying out of the additional casting operation.

The principal object of the present invention, therefore, is to provide for a casting flask of the class mentioned, and one wherein the foregoing defects and disadvantages in the structure and operation of such devices are remedied and overcome, and whereby the success of the initial casting operation 70 of any particular piece of dental work is assured.

Another object of the invention is to provide for a casting flask of the type mentioned, and one of an extremely simple and inexpensive construction and arrangement of parts, and wherein the wax pattern may be accurately embedded within the investment at the required distance from the end 75 thereof, whereby to withstand the effects of the pressure or vacuum methods of forcing the molten metal into the mold space or cavity.

A further object of the invention is to provide for a casting flask of the character set forth, and one wherein provision is made for preventing the air pressure used in forcing the molten metal into the mold space or cavity from passing through the entire 80 cross sectional area of the porous investment, such as often results in the breaking down of the weaker wall portion of the latter, or in the failure to force the molten metal into the mold through loss of this 85 pressure or suction, a means being provided whereby such pressure is exerted centrally of the body of the investment from one end to the other thereof and in line with the mold space or cavity therein, for such purpose, as well as to assure of the molten metal 90 filling the mold space or cavity, and not 95 100

otherwise being spread to an appreciable extent into the pores of the investment.

Another object of the invention is to provide for a casting flask as characterized, 5 and one wherein the end wall of the investment or mold body, in proximity to which the mold space or cavity is formed, is suitably reinforced in a manner to prevent the breaking down thereof under the effects of 10 pressures used for the forcing of the molten metal into such space or cavity.

With the foregoing and other objects in view, the invention resides in the certain novel and useful construction, arrangement 15 and operation of parts, as will be herein-after more fully described, set forth in the appended claims, and illustrated in the accompanying drawings, in which:—

Figure 1 is a vertical section through a 20 preferred embodiment of the casting flask, and showing the parts thereof in the initial or mold preparing position of operation.

Fig. 2 is a view similar to that of Fig. 1, but showing the casting flask in reversed 25 position and ready for the casting operation.

Fig. 3 is a horizontal section taken on the line 3—3 of Fig. 1.

Fig. 4 is a horizontal section taken on the 30 line 4—4 of Fig. 1, and,

Fig. 5 is a top plan view of the flask as shown in Fig. 2.

Referring to the drawing, wherein similar characters of reference designate cor- 35 responding parts throughout the several views thereof, the preferred embodiment of the invention as shown therein comprises a cylindrical flask body or casing formed to provide an upper portion 10, and a lower portion 11, said portions having their connected ends interiorly and exteriorly threaded, as at 12, for adjustable engagement one with respect to the other, the lower portion 40 11 being of a greater length than the upper portion 10, substantially as shown.

The lower portion 11 is preferably formed to provide an inturned flange portion 13 at its lower end, and has its walls slotted as at 14, for a portion of its circumference, at 45 a point immediately inward of the flange portion 13, for the insertion therethrough of a perforated removable bottom member or plate 15, the inner portion of the latter being of a width corresponding to the mean 50 diameter of the opening through the flange portion 13, and of a length to have its inner end supported on the inner wall thereof, while the outer end portion 16 is coextensive with the slot 14 and has its outer 55 edge curved on a line conforming with the curvature of the outer surface of the cylindrical body portion 11, except for a centrally and outwardly extended finger gripping portion 17, by means of which the 60 insertion and withdrawal of the plate 15

is readily facilitated. The upper portion 10 of the cylindrical body is provided with a concaved wall 18, spaced inwardly of its upper end, and which has a sprue hole 19 at its center for purposes which will be 70 herein-after more fully explained.

In the preparing of the mold, with its upper and lower portions 10 and 11 of the flask unthreaded, and with the bottom plate 15 removed from the lower portion 11, the 75

upper portion 10 is placed top side down on the top of a work-bench or other suitable support (not shown), and is centered over a sprue former 20, which is circular in form and has a convex upper face provided with an opening at its center and preferably filled with a suitable plastic material or wax filling 21 for the engagement therein of a sprue former wire 22, which is now passed downwardly through the central opening 19 formed in the concave wall 18, and has its lower end forced into the wax filling 22 within the opening of the support 20 for the purpose of supporting in proper position, within the flask body, of 80 a pattern 23 fixed on its upper end. The lower portion 11 of the flask is now screwed onto the upper portion 10, as it stands, and until the wax pattern 23 is at the desired 85 distance below the open or bottom end of the flask. This pattern 23 is in the exact form of the desired dental article or restoration to be cast, and is preferably formed of a wax capable of being readily vol- 90 atilized or otherwise destroyed under the action of heat, and to facilitate the affixing of the same in position on the sprue former or wire 22, the latter is heated for the ready penetration of one of its ends into the pattern and in a manner with the least possible chance of breakage or other injury 95 thereto.

With the parts in the position as thus de- 100 scribed, the flask body is now filled with a suitable mold forming material or investment 24 in plastic state, which is passed through the central opening 19 and fills the space between the concaved wall 18 and the convexed face of the sprue former 20, as well as the body of the flask proper, when 105 the bottom plate 15 will be inserted inwardly of the slot 14 and in a manner to have its inner end portion seat against the inner wall of the flange 13, in which condition, it is left standing until the investment ma- 110 terial 24 has hardened. The sprue former 20 is then disengaged from the flask end and the sprue wire 22, by a quarter turn, when heat is to be applied to the flask for the purpose of evaporating all moisture 115 from the investment material and for the destruction, melting or vaporizing of the wax pattern 23. By thus destroying the wax pattern 23, a mold space or cavity 23', as shown in Fig. 2, will be provided within 120 125 130

the hardened body of the plastic material or investment 24, and, upon the withdrawal of the sprue former or wire 22, a sprue duct will extend from the mold space or cavity 23' to and open through the upper end wall of the mold body or investment 24, and centrally with respect to the sprue hole 19 with the concaved wall 18 of the upper portion 10 of the flask. For the forcing 5 of the molten metal into the mold space or cavity 23', the flask is turned end for end from its original position, and the molten metal is forced downward of the sprue duct or passage 22' and into the mold space 10 or cavity 23', the air pressure used for such purpose passing downwardly of the sprue hole 19 through the pores of the mold body or investment 24, and out of the perforations formed in the bottom plate 15 at the 20 lower end of the lower portion 11 of the flask. After the mold space or cavity 23' has been filled with the molten metal, the flask is allowed to cool, when the upper part 10 thereof will be removed from the lower portion 11, preferably by softening the investment 24 by soaking in water and unscrewing the parts of the flask, when the investment 24 may be easily cleaned away from the inside of the flask and the casting 25 removed therefrom.

The positioning of the pattern 23 at a proper and necessarily predetermined distance inwardly of the lower end of the investment 24, so that a sufficient thickness 30 of the latter will be provided at this side of the mold space or cavity 23', is readily accomplished by the lengthening or shortening of the flask body, it being very essential in this particular casting art, that the wax pattern 23 be placed, at the time of its being 35 embedded in the plastic investment, at a definite distance from the lower end or bottom of the flask so that, when the molten metal is forced down through the sprue 40 hole 19, and the sprue duct 22' and into the mold space or cavity 23', it will remain 45 within the latter, since the pressure used for the forcing action will have been reduced by reason of the escape of the air through 50 the pores of the mold body or investment 24, whereas, should the mold space or cavity 23' be placed too far from the lower end or bottom 55 of the investment 24, the effects of the pressure would be such as to force a goodly portion of the molten metal into the pores 60 of the mold body or investment, since the lessened distance between the mold space or cavity 23' and the sprue hole 19 would not be sufficient to permit of the necessary rapid seepage of air through the pores of the investment for the reducing of such pressure. However, if the mold space or cavity 23' is formed too close to the lower end or bottom 65 wall of the mold body 24, the lower wall portion of the latter will be broken by the

pressure with result that the metal will run out at the bottom of the flask, causing failure to the operation as has been hereinbefore explained.

From the foregoing, it will be readily apparent that while a preferred embodiment of the casting mold or flask has been described and illustrated herein specific terms and details of construction, arrangement and operation of parts, various changes in 70 and modifications of the same may be resorted to without departing from the spirit of the invention or the scope of the claims appended thereto.

Having thus fully described the invention, 80 what is claimed, is:—

1. In a casting flask as characterized, a flask body open at one end and having a sprue hole opening centrally of the closed end thereof, said flask body being formed 85 to provide upper and lower separable sections one in threaded engagement with the other, a sprue former adapted for insertion into said flask through the sprue hole in the closed end thereof, a pattern carried at the inserted end of said sprue former and adapted 90 to be embedded in a plastic material filling said flask body, and a removable perforated plate carried at the open end of said flask body for reinforcing the plastic filling 95 during the casting operation, the separable sections of said flask body being relatively adjustable for effecting the proper positioning of said pattern within the plastic filling 100 therein.

2. In a casting flask for the purpose set forth, comprising a flask body formed to provide separable upper and lower sections, said upper section having formed integral 105 with its inner face at a point removed from the upper end thereof a concave wall formed with a centrally disposed opening, a removable perforated bottom plate engaging in the lower section in proximity to its lower end, a sprue former adapted for insertion inwardly with respect to said wall and through said opening and adapted to carry a pattern at the inserted end thereof, and means for adjusting the sections of said 110 flask body for affecting the proper positioning of the pattern on the sprue former.

3. In a casting flask for the purpose set forth, a flask body formed of a pair of sections adjustably connected together, one of said sections having formed integral with 115 its inner face a concave wall formed with a centrally disposed opening, and the other of said sections provided with a removable perforated bottom plate.

4. In a casting flask for the purpose set 120 forth, a flask body formed of an upper and a lower separable section, said upper section having formed integral with its inner face at a point removed from the upper terminus thereof a concave wall formed with a center 130

opening of materially greater diameter than a sprue former, means for supporting a pattern in position within said flask body, that section provided with said wall being of less height than the other of said sections, one of said sections overlapping the other, and said sections having inherent means for ad-

justably connecting them together for effecting the proper positioning of the pattern therein.

10

In testimony whereof, I affix my signature hereto.

NATHAN O. LYNN.
